LOOP REGULATING MECHANISM FOR
STRAIGHT KNITTING MACHINESEmil J. Berger and Howard K. West, Lansdale,
Pa., assignors to Dexdale Hosiery Mills, Lans-
dale, Pa., a corporation of Pennsylvania

Application February 12, 1948, Serial No. 7,806

4 Claims. (Cl. 66—82)

1

This invention relates to loop regulating mechanisms for straight knitting machines of the "Cotton" type ordinarily used in the commercial production of flat fashioned stocking blanks and the like.

The chief aim of our invention is to enable finer adjustments to be made in mechanisms of the kind referred to so that the size of the loops can be regulated with greater accuracy for the production of fabrics which will be uniform as to length and identical in appearance as regards the regularity of the meshes.

Other objects and attendant advantages will appear from the following detailed description of the attached drawings, wherein Fig. 1 is a view showing in front elevation part of a straight knitting machine conveniently embodying our invention.

Fig. 2 is a cross section of the organization taken as indicated by the angled arrows II—II in Fig. 1.

Fig. 3 is a fragmentary detail sectional view taken as indicated by the angled arrows III—III in Fig. 1, and

Fig. 4 is a fragmentary detail sectional view taken as indicated by the angled arrows IV—IV in Fig. 2.

The knitting machine chosen for convenience of exemplifying our invention is generally of the construction disclosed in U. S. Patent 1,982,991 granted to Kenneth Howie and Charles C. Kriebel on December 4, 1934, in that it has a bar 1 with a series of needles 2, and sinked elements such as shown at 3 in Fig. 2 to cooperate with the needles in formation of the fabric loops in a well known manner. The needle bar 1 is supported by a yoked arm 4 pivotally connected at 5 to the ends of horizontal lift arms 6 on a longitudinally-extending rock shaft 7. Through a roller arm (not shown) actuated by a rotary cam (not shown) on the cam shaft 8 of the machine, the rock shaft 7 is oscillated to impart up and down movements to the needle bar 1 as required in stitch formation. In and out movements are at the same time induced in the needle bar 1 by oscillation of the yoke bracket 4 about the pivots 5. As shown the bracket 4 is provided with a pendant extremity 4a which, through a releasable link bar 9, is connected to the press arm 10 which is free on shaft 7 and has a roller 11 thereon running on the periphery of the rotary press cam 12 on the cam shaft 8. Affixed to the usual loop regulating shaft 13 is an arm 14 with a roller 15 adapted to be contacted by the stitch cam 16 on the cam shaft 8. As in the patent hereinbefore

referred to, the arm 10, at its swinging end, has a lug projection 10a which is bored and tapped to receive individually-adjustable stop abutments in the form of screws 17 and 18. Arranged to coact with the stop screws 17 and 18 is a wing-like arm 19 which is pinned to the loop regulating shaft 13 and whereon is pivoted at 21, a shiftable finger 22. Normally this finger 22 is interposed beneath the stop screw 18 as illustrated and when so placed, prevents the stop screw 17 from contacting the element 19. As ordinarily, the head 17a of screw 17 is provided with circumferential graduations, see Fig. 1, to indicate the different positions to which it may be adjusted. Shiftable 5 in a longitudinal groove 23 in the fulcrum boss of element 19 is a slide 25 having teeth at one end in mesh with a gear sector 22a on the finger 22, and slide being secured at its opposite end to a collar 26 which is keyed against rotation but shiftable along the loop regulating shaft 13 in 10 opposition to a spring 27 in compression between it and a fixed frame member 28. When the collar 26 is so shifted, the finger 22 is swung from beneath the stop screw 18 through co-action 15 of the teeth on bar 25 with the sector teeth 22a to allow the stop screw 17 to contact the element 19 for change in stitch length in the known manner. Attached at one end to the collar 26 is a metallic tape 29 which passes about a 20 grooved guide roll 30 and has its opposite end secured to the tail of a finger 31 freely fulcrumed on a fixed stud 32. As shown, the end of the finger 31 lies in the path of a series of cam rises 33—37 circumferentially of the usual timing drum 41 of the machine. Free in the interval between the spaced boss portions 14a and 14b of the roller arm 14 on shaft 13, see Fig. 1, is an upwardly reaching lever 42 which has a pendant lug projection 42a with a stud 43 therein to cooperate 25 with a cam element 45 pivoted at 47 to a cross web 14c whereby the two boss portions of said roller arm are integrally united. Through a drop link 48, the cam element 45 is connected to the tail of a finger 31, see Fig. 2, which is freely fulcrumed on the stud 32 alongside the finger 31, with its end in the path of a cam rise 50 on the timing drum 41. At its upper end, the lever 42 carries a pin 52 which is engaged by the devised lower end of a swing lever 53 freely suspended 30 from another longitudinal shaft 55 of the machine. The lever 53 has a point projection 53a arranged to be acted upon by circumferentially-spaced lateral segmental cam projections 56, 57 and 58 of a cam disk 59 on a separate horizontal cam shaft 60 of the machine by which the stitch

length is changed during splicing of the stocking heels, insteps and toes. The spring indicated at 61 is influential upon the arm 14 to maintain the roller 15 of the latter yieldingly engaged with the cam 16 and the other parts all positioned as shown in Fig. 2.

The elements thus far described have their counterparts in the Howie patent, supra, identical and function as and for the purposes set forth therein. In accordance with our invention however, the portion 52a of pin 52 engaged in the lever 42 is eccentric to the portion thereof which is engaged in the clevis of lever 53, see Fig. 4. Accordingly, by rotative adjustment of the pin 52 it is possible to minutely vary the angularity between the levers 42 and 53 and so vary the stitch length for the splicing of the heel, instep and toe portions of the stockings under control of the disk 59, such adjustments being independent of and non-influential upon the adjustments of the screw 17. In order to visually indicate different positions to which the pin 52 may be adjusted, and to enable quick and accurate re-settings, we have provided a pointer 62 for co-ordination with a graduated scale sector 63 keyed to 52a, the pointer being secured by dowel pins 64, see Fig. 4, to the upper end of the lever 42 and the sector keyed to the eccentric portion 52a of said pin and held in place by the nut at 51.

Having thus described our invention, we claim:

1. Loop regulating mechanism for straight knitting machines having a loop regulating shaft with an affixed arm arranged to be actuated by a rotary cam on the cam shaft of the machine, a second arm on the loop regulating shaft contacted by an abutment on a press arm arranged to be actuated by a press cam on the cam shaft, and a lever on the press cam having a pivotal connection at its outer end with the corresponding end of a freely fulcrumed swing lever arranged to be actuated by coaction laterally with circumferentially spaced projections of a rotary cam on a separate cam shaft; wherein the pivotal

connection aforesaid comprises a pin which is rotatively adjustable in the end of one of the levers and which has an eccentric portion engaged in the end of the other lever.

2. The invention according to claim 1, in which there is a graduated scale sector on the lever that carries the pin, and in which a coordinating adjustment indicating pointer is secured to the pin.

3. Loop regulating mechanism for straight knitting machines having a loop regulating shaft with an affixed arm arranged to be actuated by a rotary cam on the cam shaft of the machine, a second arm on the loop regulating shaft contacted by a screw adjustable in a press arm arranged to be actuated by a press cam on the cam shaft, and a lever on the press cam having a pivotal connection at its outer end with the corresponding end of a freely fulcrumed swing lever arranged to be actuated by coaction laterally with circumferentially spaced projections of a rotary cam on a separate cam shaft; wherein the pivotal connection aforesaid comprises a pin which is rotatively adjustable in the end of one of the levers and which has an eccentric portion engaged in the end of the other lever.

4. The invention according to claim 3, in which there is a graduated sector scale on the lever that carries the pin, and in which a coordinating adjustment indicating pointer is secured to the pin.
